Attorney

UNITED STATES PATENT OFFICE.

LOUIS F. DICKMAN, OF COVINGTON, KENTUCKY.

LOCKING DEVICE FOR DRAIN-VALVE OPERATING RODS.

Application filed May 16, 1927. Serial No. 191,766.

The present invention relates to release valves associated with the auxiliary reservoirs of the air brake system on railway cars, and has reference more particularly to 5 a device for locking the pull rod associated with the release valve in an outwardly pulled position to permit the auxiliary reservoir to be bled until the brakes are entirely disengaged from the wheels.

10 One of the important objects of the present invention is to provide a means for locking the pull rod in its outermost pulled position for maintaining the release valve open, said locking means being automatically released by the jar or vibration of a car when the latter is being coupled up with another car.

20 A still further object is to provide a locking device of the above mentioned character which will at all times be positive and efficient in carrying out the purposes for which it is designed, the same being further simple in construction, inexpensive, and strong and durable.

25 Other objects and advantages of the invention will become apparent from the following description taken in connection with the accompanying drawing.

In the accompanying drawing wherein like numerals indicate like parts throughout the several views:

30 Figure 1 is a side elevation of the locking device embodying my invention showing the same in actual use in locking one of the pull rods in its outermost position.

Figure 2 is a detail perspective view of the inverted U-shaped bracket.

Figure 3 is a similar view of the locking pawl, and

40 Figure 4 is a detail perspective view of the rack member forming a part of the present invention.

In the drawing wherein for the purpose of illustration is shown the preferred embodiment of my invention, the numeral 1 designates the bottom portion of a railway car, beneath which is supported the auxiliary reservoir 2 of the air brake system. Associated with this auxiliary reservoir is a 45 normally closed release valve designated generally by the numeral 3, cooperating with this release valve in the conventional

manner is the rocker lever 4. As the release valve is of the well known construction, a detail description thereof in the present application is thought unnecessary.

Operatively connected to the respective ends of the rocker lever 4 are the pull rods 5, the outer ends thereof extending laterally beyond the opposite sides of the car 1 and 55 the outer end of each pull rod is formed with an actuating handle 6.

A guide 7 depends from the bottom of the car at each side thereof and this guide is formed with a transverse opening 8 through 60 which the outer end portion of the respective pull rod extends.

At the present time, when it is desired to release the air from the auxiliary reservoir 2, the operator pulls outwardly on the handle 6 of either pull rod and is obliged to hold the rod in its outwardly pulled position until all the air has been released from the reservoir and this operation requires the expenditure of a considerable length of time.

It is therefore one of the salient objects of the present invention to provide a means for locking the pull rod in its outwardly pulled position, thus obviating the necessity of having to manually hold the handle 6

70 while bleeding the air brake system, and to this end, I provide a substantially inverted U-shaped bracket 9 which is formed from strap iron and this bracket is adapted for disposition through the opening 8 formed 75 in the guide 7, it being of course understood that the arm 10 is initially disposed in the same horizontal plane as the crown or base portion 11 in order to permit the bracket to be properly positioned through the slot

80 or opening 8 and when the crown portion 11 is properly positioned in the slot or opening 8, the inner arm 10 is then bent downwardly for disposition against the inner side of the guide in the manner clearly 85 shown in Figure 1. The other arm 12 of this inverted U-shaped bracket 9 has formed on its lower free end a looped portion 13,

90 the purpose of which will be presently described. There is sufficient space within the opening or slot 8 to accommodate both the pull rod 5 and the bracket without interfering with the sliding movement of the 95 pull rod.

A pawl in the form of a flat strip which is designated by the numeral 14 is formed at its inner edge with the spaced looped portions 15 between which is disposed the 5 looped portion 13 formed on the lower free end of the outer arm 12 of the inverted U-shaped bracket 9, and a suitable pin 16 extends through the registering looped portions 13 and 15 for pivotally connecting 10 the inner end of the pawl to the lower end of the outer arm 12 of the bracket 9.

A weight is provided on the bottom of the forward end portion of this pivoted pawl 14 and the outer free end of the pawl 15 is beveled as is clearly illustrated in Figure 3.

The locking means further comprehends the provision of a rack member which comprises a plate 18 adapted to be secured on 20 the outer end portion of the pull rod 5 adjacent the handle 6 by means of suitable clamps 19, the plate 18 being formed with openings 20 to accommodate said clamping means. The bottom face of the plate 18 is 25 formed with the transversely extending ratchet teeth 21 and with which the beveled outer end of the pivoted pawl 14 is adapted for cooperation in the manner to be presently described.

In the operation of my invention, the trainman pulls outwardly on the handle 6 as usual and thereby opens the release valve 3 and the pivoted pawl 14 is brought 30 into engagement with the ratchet teeth 21 formed in the bottom face of the plate 18, and due to the tendency of the spring associated with the release valve to normally urge the pull rod inwardly, said pivoted pawl will be maintained in locking engagement with one of the ratchet teeth, thereby holding the pull rod in its outwardly pulled 35 position so that the air in the auxiliary reservoir 2 may be entirely exhausted therefrom.

The locking means is automatically released by the jar or vibration of the railway car caused when the car is moved and manifestly such jarring action will disengage the pawl 14 from engagement with the ratchet 40 teeth 21 formed in the bottom face of the plate 18 and the weight 17 associated with the pivoted pawl will cause the same to swing downwardly entirely out of the way of the pull rod and the rack member carried thereby and the spring controlled release 45 valve will automatically be moved to a closed position and will simultaneously move the pull rod inwardly to its normal position.

It will thus be seen from the foregoing 50 description that I have provided a highly novel yet simple device for locking a pull rod for actuating the release valve of the auxiliary reservoir of an air brake system of a railway car so that it will not be nec-

essary for a trainman to hold the pull rod in its outermost position, and furthermore a device of this character will at all times be positive and efficient in its operation and will not necessitate the alterations of the 70 parts of the railway car with which the device is associated in installing the same.

While I have shown the preferred embodiment of my invention, it is to be understood that various changes may be made 75 in the size, shape and arrangement of parts without departing from the spirit of the invention and the scope of the appended claims.

Having thus described the invention, what 80 I claim as new is:

1. In combination with a railway car, and the auxiliary air brake reservoir having a normally closed drain valve, a pull rod for operating the valve, a guide at the side of 85 the car provided with a slot through which the pull rod extends, a substantially inverted U-shaped bracket having its base portion disposed within the slot, the arms being arranged on opposite sides of the guide, a rack 90 member carried by the outer end portion of the pull rod, and a pawl pivoted on the outer arm of the inverted U-shaped bracket, the free end of the pivoted pawl adapted for engagement with the rack member for holding 95 the rod in its outwardly pulled position, said pivoted pawl adapted to be released automatically from engagement with the rack member by the jar of the car.

2. In combination with a railway car, and 100 the auxiliary air brake reservoir having a normally closed drain valve, a pull rod for operating the valve, a guide at the side of the car provided with a slot through which the pull rod extends, a substantially inverted 105 U-shaped bracket having its base portion disposed within the slot, the arms being arranged on opposite sides of the guide, a rack member carried by the outer end portion of the pull rod, a pawl pivoted on the 110 outer arm of the inverted U-shaped bracket, the free end of the pivoted pawl adapted for engagement with the rack member for holding the rod in its outwardly pulled position, said pivoted pawl adapted to be released automatically 115 from engagement with the rack member by the jar of the car, and a weight associated with the free end portion of the pivoted pawl.

3. In combination with a railway car, and 120 the auxiliary air brake reservoir having a normally closed drain valve, a pull rod for operating the valve, a guide at the side of the car provided with a slot through which the pull rod extends, a substantially inverted 125 U-shaped bracket having its base portion disposed within said slot, the arms being arranged on opposite sides of the guide, a rack member carried by the outer end portion of the pull rod, a pawl, interfitting 130

loops formed at the adjacent ends of the pawl and the outer arm of the inverted U-shaped bracket, a pin extending through said interfitting loops whereby said pawl is 5 pivotally secured to said arm, the free end of the pivoted pawl adapted for engagement with the rack member for holding the pull

rod in its outwardly pulled position, said pivoted pawl adapted to be released automatically from engagement with the rack by 10 the jar of the car, and a weight carried by the free end portion of the pivoted pawl.

In testimony whereof I affix my signature.
LOUIS F. DICKMAN.
